COMBINATION ARTICLE

Mario D'Onofrio, Baltimore, Md.

Application November 7, 1939, Serial No. 303,335

7 Claims.

(CL 24—3)

This invention relates to improvements in combination articles for pocket use, and with regard to its more specific aspects to a combined bill clip, key sheath and key.

5 Among the objects of the present invention may be noted the provision of a novel combination article for pocket and/or personal use which possesses a high degree of utility, which is attractive and neat in appearance, and which is of a size as to be readily carried in one's pocket; the provision of a combined bill clip and key device possessing the above characteristics and which is particularly adapted for masculine use; the provision of a bill clip providing a carrier for a key; 10 the provision of a bill clip of which one of the jaws thereof carries or otherwise provides a sheath or housing adapted to removably support a key or a blank from which the finished key may be cut; and the provision of a combination article in the nature of a bill clip providing a key sheath, with a key organized therewith in ornamental and practical manner.

20 Other objects will be in part obvious and in part hereinafter pointed out in connection with the following analysis of this invention wherein is illustrated an embodiment of the invention in detail.

In the drawing—

25 Fig. 1 is a front elevation of a combination article in accordance with the present invention;

Fig. 2 is a perspective view of the combination article shown in Fig. 1; and

Fig. 3 is a section along lines 3—3 of Fig. 1.

In the drawing, wherein like reference characters designate like parts throughout the several views, the reference character 10 designates the rear jaw and reference character 11 the front jaw of a bill clip, the jaws being joined along their relatively top edges as by a connecting web

40 12. As shown, the rear jaw 10 may be formed or shaped as a rectangular frame, and the front jaw 11 is tongue-shaped and of a length such that its lower end, which may be curved and beaded forwardly as at 13, extends over the lower 45 cross piece of the rear jaw. Preferably, the tongue along its top is provided with ornamental wings 14, 15 integrally formed therewith.

The clip is adapted to be stamped from a blank of metal stock of sufficiently springy nature that 50 one or more folded bills, such as bank notes, may be inserted between the jaws when the latter are bent to overlying relation as shown and securely held thereby against disengagement. Precious metal stock may be employed in fashioning clips 55 as aforesaid for the quality trade, although for

the novelty and cheaper trade plated metal stock or stock of the baser metals may be employed.

Carried by the tongue-shaped front jaw on its front face is a key sheath or housing 20. As shown, the sheath is open at both its ends and may be comprised by a U-shaped stamping, preferably of the same metal stock as the clip proper, to provide side pieces 20a and a cross or bridging piece 20b. Preferably, the side pieces are secured along their free or relatively lower edges as by welding to the jaw 11, whereby the jaw forms one side of a rectangular enclosure.

The relatively upper edge of the sheath may be formed thick as by providing therealong a beading 21. While the beading 21 adds to the ornamental appearance of the sheath, it also serves a reinforcing function. Preferably, the bead 21 may curve upwardly, thus to provide an arcuate lip for the purpose to be hereinafter stated.

The side pieces 20a of the sheath 20 may be 20 extended upwardly of the bead 21 to form extended side pieces 22 which connect with a transverse guide piece 23 which extends between the side pieces 22 and which is spaced from the front face of the jaw piece 11 substantially the thickness of a key blank. Intermediate its ends the guide piece 23 is provided with a rearwardly extending and V-shaped tang 24 adapted to engage in the longitudinal groove with which a key or key blank is conventionally provided.

The upper edges of the side pieces 22 are spaced a predetermined vertical distance from the lower open end of the sheath 20, this spacing being somewhat less than the length of the shank of a key adapted to be inserted in the 35 sheath 20, whereby the tip of the key shank positioned in the sheath may extend a small distance below the sheath, in the manner clearly indicated in Fig. 1.

In merchandising the combination article of 40 the present invention, the article as sold to the trade will comprise the bill clip generally as described and which carries the key or key blank sheath 20. Additionally, the purchaser will be provided with a key blank of special construction, to be described, the shank of which is housed in the sheath 20. It is intended that the purchaser will have the key blank cut or otherwise shaped to duplicate a key already in his possession, whereby the key carried by the bill clip provides a spare or extra key for such use as the purchaser may desire to make of it. Thus, if the purchaser has the key blank cut to duplicate the ignition key of his automobile, for example, and such duplicate key is carried in the bill clip 45 50 55

containing his money, which he is most unlikely to forget or misplace, the spare key is hence available at all times even though the original key may have been lost or misplaced.

5 To this end, the clip-carried sheath 20 is provided for the purpose of housing a key blank, of the character generally indicated in the drawing, and which is comprised by a shank or blade 27 and a head 28. Preferably, the head 28 has 10 a hinged connection with the shank 27 by means of a pintle and ear-type hinge 29. Thus the head 28 may in its normal operating position be swung to a position in which it extends substantially in the plane of the shank 27. When inserted in the sheath, however, the head 28 may be folded over the shank 27, thus to reduce the overall length of the key. The shank 27 is preferably of the character having on one face a longitudinal fluting or groove 30 into which, as the 15 key shank is moved into the sheath 20, the tang 24 of the guide bar 23 is adapted to engage.

In inserting the key blank into the sheath, the shank 27 thereof is inserted between the side pieces 22 and beneath the guide bar 23 which 20 project upwardly from the sheath. As the key shank is projected downwardly into the sheath, it is guided in such movement by the side pieces, the guide bar and also the tang 24 which, as above stated, engages in the key shank fluting 25 30. The key shank is moved downwardly into the sheath 20 until its abutment stops 31 engage the upper edges of the side pieces 22 which serve to limit further insertion of the key into the sheath 20. With the spacing between the top edges of 35 the side pieces 22 and the lower end of the sheath 20 being somewhat less than the length of the key shank, the tip thereof protrudes a slight distance beyond the sheath 20, as indicated in Fig. 1.

With the key shank so housed within the 40 sheath 20, the key head 28 is swung to a position in which it overlies the shank 27. The depth of the key head is such that when the head is so swung, its then lower edge may engage and spring past the lip-shaped bead 21 of the sheath, 45 thereby to latch the key blank to the sheath and hence to the clip proper. It will be understood that dimensioning of the sheath 20 and the spacing between side pieces 22, as well as the spacing between the guide bar 23 and the front face 50 of the clip jaw 11, is such that the key shank is held snugly in its position as aforesaid, suitable clearance being provided, however, so that the key may be readily projected into and removed from its sheath.

55 As will be further seen from Fig. 1, the key head is provided with an opening 32 whereby, when the head is swung to its latching position with reference to the sheath bead 21, it may clear the guide bar 23. It will be here noted that the height of the side pieces 22 is reduced so that the key head may be moved into latching position beneath the bead 21.

By the above arrangement the key blank may be removed from its sheath 20 by the simple operation of grasping the bill clip in the palm of the hand and by flicking the thumb nail upwardly against the protruding tip of the key shank. This slight pressure is sufficient to unlatch the key head from the sheath bead 21, 65 whereupon the key head 28 may be swung to its normal position and the key bodily withdrawn from the sheath 20.

70 While in the foregoing the bill clip has been described to comprise a rear jaw of rectangular configuration and a tongue-shaped front jaw, 75

it will be understood that jaws otherwise shaped may be employed, so long as the jaws possess such shape and size as to engage a substantial area of the bill gripped thereby. It is also within the contemplation of the present invention 5 that the sheath 20 and its related guide parts 22, 23 may be formed integrally with the front jaw 11 as by stamping such parts from the metal forming the front jaw.

Accordingly, as many changes could be made 10 in carrying out the above constructions without departing from the scope of the invention, it is intended that all matter contained in the above description or shown in the accompanying drawing shall be interpreted as illustrative and not 15 in a limiting sense.

I claim:

1. A key sheath for mounting on one of the jaws of a bill clip comprising an enclosing structure adapted to be secured against the relatively 20 outer face of said one jaw, said structure including spaced side pieces and a bridging face which form with the jawpiece a housing adapted to receive the shank of a key, and means operatively related to the side pieces for guiding a key 25 shank into said housing and for frictionally securing the shank in substantially housed position therein.

2. A key sheath for mounting on one of the jaws of a bill clip comprising an enclosing structure adapted to be secured against the relatively 30 outer face of said one jaw, said structure including spaced side pieces and a bridging piece which form with the jaw face a housing adapted to receive the shank of a key, said side pieces 35 being extended beyond the bridging piece and carrying a transversely extending piece operative to guide a key shank into the housing and to frictionally secure the shank in substantially housed position therein. 40

3. A key sheath for mounting on one of the jaws of a bill clip comprising an enclosing structure adapted to be secured against the relatively 45 outer face of said one jaw, said structure including spaced side pieces and a bridging piece which form with the jaw face an open-ended housing adapted to receive the shank of a key and which is of lesser depth than the key shank, said side pieces carrying a transversely extending 50 guide piece disposed relatively above the upper edge of the bridging piece for guiding the shank of a key into said housing.

4. In a key and key-sheath assembly, the combination of a key having a shank and a head 55 pivotally related thereto, the sheath providing a housing for the key shank and including means for guiding the shank into the housing, the key and sheath being so constructed and arranged that upon pivoting of the head to a position overlying the shank of a key received in said housing the key head engages the upper edge of the housing and thereby frictionally secures the key in substantially housed position within the housing. 60

5. In a key sheath and bill clip assembly, the combination of a bill clip constituted by spaced jaw members, and a key sheath comprising an enclosing structure secured against the relatively 65 outer face of one of said jaw members, said structure including spaced side pieces and a bridging piece which form with the jaw face a housing adapted to receive the shank of a key, and means operatively related to the side pieces 70 for guiding a key shank into said housing and 75

for frictionally securing the shank in substantially housed position therein.

6. In a key sheath and bill clip assembly, the combination of a bill clip constituted by spaced jaw members, and a key sheath comprising an enclosing structure secured against the relatively outer face on one of said jaw members, said structure including spaced side pieces and a bridging piece which form with the jaw face a housing adapted to receive the shank of a key, said side pieces being extended beyond the bridging piece and carrying a transversely extending piece operative to guide a key shank into the housing and to frictionally secure the shank in substantially housed position therein.

7. In a key, key sheath and bill clip assembly,

the combination of a bill clip constituted by spaced jaw members, a sheath comprising an enclosing structure adapted to be secured against the relatively outer face of one of said jaw members, and a key having a shank and a head pivotally related thereto, the sheath providing a housing for the key shank and including means for guiding the shank thereinto, the key and sheath being so constructed and arranged that upon pivoting of the key head to a position overlying the shank of a key within said housing the key head engages the upper edge of the housing and thereby frictionally secures the key to the housing. 5 10
